UNITED STATES PATENT OFFICE.

GEORGE D. H. GAY, OF BATH, MAINE, ADMINISTRATOR OF THE ESTATE OF GRANVILLE WARE GAY, DECEASED.

IMPROVEMENT IN MEDICAL COMPOUNDS FOR THE CURE OF FEVER AND AGUE.

Specification forming part of Letters Patent No. 126,882, dated May 21, 1872.

Specification of a certain compound called Gay's Fever and Ague Remedy, invented by G. WARE GAY, M. D., of Bath, in the county of Sagadahoc and State of Maine, as a specific and preventive for fever and ague.

To prepare this compound in the quantity of a pint, take powdered muriate of ammonium, eighty grains; sulphate of quinine, thirty grains; fluid extract dandelion (U. S.) eighty drops; tincture capsicum (U. S.) one hundred and sixty drops; essence of cinnamon (U. S.) four fluid drams; Fowler's solution, two fluid drams; spirits lavender compound, one and a half fluid ounce; simple sirup, three fluid ounces; Holland gin, eight fluid ounces; aqua fontana, in sufficient quantity to make sixteen fluid ounces.

Dissolve eighty grains of muriate of ammonia in one fluid ounce of water; then dissolve thirty grains of sulphate of quinine in one fluid ounce of water, by adding diluted sulphuric acid in sufficient quantity; then add eighty drops fluid extract dandelion; one hundred and sixty drops tincture of capsicum; essence of cinnamon, four fluid drams; spirits of lavender compound, one and a half fluid ounce; simple sirup, three fluid ounces; Holland gin, eight fluid ounces; and lastly, a sufficient quantity of water to make the whole measure sixteen fluid ounces.

Directions.

First take a dose of cathartic medicine to clear the stomach and bowels of phlegm and vitiated bile; then take one-half wine-glassfull of the remedy three times a day, one hour before meals. The first dose should be taken one hour before time for a chill. One dose in the morning should be taken for a few days after the chills are broken or ceased.

I claim—

The fever-and-ague remedy, herein described, composed of the above-named ingredients or their equivalents, compounded substantially as set forth.

GEORGE D. H. GAY,
Administrator.
